UNITED STATES PATENT OFFICE.

JAMES H. MINER, OF LUMBERTON, MISSISSIPPI.

WHEEL-FRANGE LUBRICATOR.

1,083,901.

Specification of Letters Patent.

Patented Jan. 6, 1914.

Application filed May 18, 1912, Serial No. 697,640. Renewed April 8, 1913. Serial No. 759,763.

To all whom it may concern:

Be it known that I, JAMES H. MINER, citizen of the United States, residing at Lumberton, Mississippi, have invented certain new and useful Improvements in Wheel-Frange Lubricators, of which the following is a specification.

My present invention relates to improvements upon wheel frange lubricators of the type employing a swinging receptacle for containing oil or other fluid lubricant, and carrying a pad adapted to be saturated with the oil and to contact with the wheel frange on the swinging of the oil container.

15 The present invention has, among others for its object, to provide means whereby oil will be fed to the pad, only when the same is swinging into contact with the wheel frange, the flow of oil at other times being cut off.

20 I have further aimed to improve the lubricator in respects which will hereinafter appear.

With these and possibly other objects in view, the invention includes the novel features of construction and arrangement and combination of parts hereinafter described and particularly defined by the appended claims.

An embodiment of the invention is illustrated in the accompanying drawings, in which—

Figure 1 is an elevation showing the oiling device in proximity to a wheel, which is representative of a wheel of any vehicle traveling upon rails; Fig. 2 is a part sectional elevation showing the pad in contact with the wheel frange and with the valve open.

Referring by reference characters to this drawing, the numeral 1 designates the wheel and 2 the oil reservoir, which may be of any suitable size and shape, and which contains within it a tube 3 preferably of curved form and extending from the upper front corner to the lower rear corner, as shown, being open at both ends but closed to the interior of the oil receptacle except for the valve opening 3a. The receptacle is supported from a suitable hanger carried by the truck by means of a leaf spring 4 which is designed to normally support the receptacle with the end 5a of the wick 6 contained in the tube just out of contact with the wheel frange. When the wheel strikes a curve, 55 the centrifugal action causes the container

to swing, the spring 4 yielding sufficiently for this purpose, with the result that the pad is brought into contact with the wheel frange to lubricate the same. Under normal conditions and with the parts in the 60 position shown in Fig. 1 the valve opening to the tube is closed by a valve 6, which extends upward through the top of the container and has its upper end connected to one arm of a rocking lever 7. The other 65 arm of this lever is normally inclined upwardly in such a position as to be pressed upon by the lower end of a leaf spring 8, when the container swings, this action pressing downwardly upon the inclined portion 70 of the lever, and rocking it on its pivot to cause the valve to be opened. The leaf spring is capable of being adjusted to vary the amount or time of opening by means of set screw 9 passing through the leaf spring 75 8 and engaging the hanger 10. I use within the tube 3 a cylindrical wick which, as before stated, is indicated at 5, and which is capable of being inserted through the open upper end of the tube and pushed down into 80 proper position, and I prefer to make this tube of felt with a metal center or core to reduce wear.

I do not limit myself to the exact construction shown, as this may be changed materially without departing from the spirit of my invention.

Having thus described my invention what I claim is:

1. In combination with a railway truck 90 and wheel, an oil receptacle supported from the truck in proximity to the wheel frange and capable of swinging toward and from the frange, a lubricating pad carried by said receptacle for contacting with the frange, 95 and means controlled by the swinging of the receptacle for governing the feed of oil from the receptacle to the pad.

2. A wheel frange lubricator comprising a swinging wheel receptacle having a lubricating pad and means controlled by the swinging of the receptacle for controlling the feed of oil from the receptacle to the pad, and means for adjusting the feed of oil. 100

3. A wheel frange lubricator comprising a swinging receptacle, a wick tube passing through the same and containing a wick, a valve controlling a passage from the receptacle to said wick tube, and means con- 105 110

trolled by the swinging of the receptacle for opening and closing said passage.

4. A wheel flange lubricator comprising a swinging lubricant receptacle, a wick tube 5 having a passage communicating with the interior of the receptacle, a wick in said tube, a valve controlling said passage, a lever operating said valve, and an adjustable contact device coöperating with said

lever to effect the opening and closing of 10 the valve on the swinging of the receptacle.

In testimony whereof, I affix my signature in presence of two witnesses.

JAMES H. MINER.
